tebau, Granichen, SwitzerlandApplication March 28, 1946, Serial No. 657,748
In Switzerland April 3, 1945

3 Claims. (Cl. 230—52)

1

The invention relates to a refrigerator of the compressor-condenser-expander type, in which the inlet or filling stroke of the compressor piston is effected by the pressure of the refrigerating medium vapour, and the compression stroke of the compressor piston is effected by an automatically cut-in auxiliary force.

It is known to provide as the auxiliary force an electric motor which operates a lifting device provided for the compressor piston.

Contrary to this, according to the invention a driving piston cooperates with the compressor piston in such manner that it follows the inlet stroke of the compressor piston and effects the compression stroke of the latter, the driving piston being moved by means of liquid under pressure which is automatically controlled as desired. This permits of a particularly cheap construction of the refrigerating installation in respect of manufacturing and maintenance costs.

The accompanying drawing shows partly in section and partly diagrammatically, as an example, one way of carrying out the invention.

In a cylinder 1 is a piston 2 serving for compressing the refrigerating medium. At its upper end, the cylinder 1 is connected by pipes 3 and 4 to the upper end of an evaporator or expander and a condenser or liquefier, not shown. Liquid refrigerating medium supplied is evaporated in the expander with absorption of heat, and liquefied in the condenser with emission of heat. Expander and condenser are connected together at the lower end by a pipe in which there is fitted a throttle valve controlled by a float or by temperature responsive means, not shown. A spring-loaded inlet valve 5 and a spring-loaded outlet valve 6 are arranged in the upper end of the cylinder 1. Connected coaxially to the lower end of the compressor cylinder 1 is a pressure cylinder 7, in which is a driving piston 8 kept at a distance from the compressor piston 2 by means of a rod 9. The driving piston 8 is constructed as a hollow cylinder which, on its downward movement, slides over a filling inset 10 provided in the pressure cylinder 7 and which at the same time serves for limiting the downward stroke of the driving piston 8 and thus of the compressor piston 2.

A main pipe 11 leading from a storage container, not shown, of the driving liquid is connected to the lower end of the pressure cylinder 7, and a gear pump 12 or other kind of conveyor pump is connected in this pipe and is adapted to be driven preferably by an electric motor. The main pipe 11 is also connected through a branch pipe 13, in which is fitted a non-return valve 14,

2

with an auxiliary cylinder 15 in which there is a piston 16. On this piston 16 a compression spring 17 acts, the tension of which is adjustable by means of a screw 18 which carries a plate 19 serving as an abutment for the spring 17. To the pressure cylinder 7 there is connected, by means of an outflow pipe 20, a subsidiary cylinder 21 in which there is a double piston 22, 23 acted on by a compression spring 24. The tension of the spring 24 is adjustable by means of a screw 25 which holds a plate 26 serving as an abutment for the spring 24. Between the branch pipe 13 and the subsidiary cylinder 21 there is provided a connecting pipe 27. A branch pipe 28 leads directly from the main pipe 11 to the subsidiary cylinder 21 which, by means of two return pipes 29 and 30 connected thereon at different levels, directly communicates with the storage reservoir 39 of the pressure liquid. The pressure cylinder 7 also communicates by a return pipe 31 directly with the said storage reservoir 39.

Assuming that the driving piston 8 provided in the pressure cylinder 7 is moved upwards by the liquid under pressure, e. g. oil, delivered by means 25 of the pump 12 through the main pipe 11 to the pressure cylinder 7, this movement is transmitted by the rod 9 to the compressor piston 2 which forces the gas in the compressor cylinder 1 through the valve 6 and the pipe 4 into the condenser. At the working position indicated, no liquid under pressure can pass out of the branch pipe 28 leading from the main pipe 11, into the subsidiary cylinder 21, since the aperture 32 in question on the subsidiary cylinder 21 is closed 30 by the upper piston 23 of the double piston 22, 23. On the contrary, fluid under pressure flows through the branch pipe 13 also running from the main pipe 11 (and through its non-return valve 14) to the auxiliary cylinder 15, so that the piston 16 is moved upwards overcoming the counterforce exerted by the compression spring 17. When the upwardly moving driving piston 8 in the pressure cylinder 7 uncovers the aperture or port 33 thereof to the outflow pipe 20, liquid under pressure flows into the subsidiary cylinder 21 whereby the double piston 22, 23 is moved upwardly therein, overcoming the counterforce exerted by the compression spring 24. Afterwards the apertures 32 and 34 in the subsidiary cylinder 21 are simultaneously opened by the upwardly moving double piston 22, 23. In this way the outflow pipe 20 is connected through the inner space of the subsidiary cylinder 21, the opening 34 and the connecting pipe 27 to the branch pipe 13; the 45 non-return valve 14 provided in the latter pre-

vents the return flow of the liquid under pressure to the main pipe 11 through the branch pipe 13. The compression spring 17, acting in the auxiliary cylinder 15 on the piston 16, is stronger, e. g. three times as strong, as the compression spring 24 acting on the double piston 22, 23 in the subsidiary cylinder 21, so that liquid under pressure now flows out of the auxiliary cylinder 15, the compression spring 17 expanding and the piston 16 moving downward forcing liquid through the connecting pipe 27 into the subsidiary cylinder 21, thus assisting the further upward movement of its double piston 22, 23 which consequently finally completely uncovers, in the subsidiary cylinder 21, the opening 35 of the return pipe 29 leading to the storage reservoir 39 and the opening 32 of the branch pipe 28. Thus by reversing the flow of the liquid under pressure and causing it to flow back into the storage reservoir 39 at a predetermined upper terminal position of the compressor piston 2, the reversal of its direction of movement has been completed. Following thereafter, the compressor piston 2 is moved downwards under the pressure effect of the cooling medium vapour flowing from the expander through the pipe 3 into the compressor cylinder 1.

The driving piston 8 accompanies this movement, whereby it closes the aperture 33 provided in the pressure cylinder 7, and thus no liquid under pressure flows any longer through the branch pipe 20 to the auxiliary cylinder 21. The double piston 22, 23 previously moved upwards in the auxiliary cylinder 24 by the liquid under pressure, first stays in its corresponding upper position as long as the liquid under pressure below the lower piston 22 in the subsidiary cylinder 21 cannot escape. Only when the driving piston 8 is approaching its lower terminal position, does it again release the aperture 33 of the pressure cylinder 7, a circumferential groove 36 on the driving piston 8 coming within the range of the said aperture 33. Consequently the liquid under pressure below the lower piston 22 of the double piston 22, 23 then flows with the slackening of the compression spring 24 and corresponding downward movement of said double piston, out of the auxiliary cylinder 21 through the outlet pipe 20 to the pressure cylinder 7. The annular space formed by means of the circumferential groove 36 of the driving cylinder 8 between the latter and the inner wall of the pressure cylinder 7, also extends over an opening 37 in the pressure cylinder 7 associated with the return pipe 31, so that the liquid under pressure flowing into this annular space through the outlet pipe 20 from the subsidiary cylinder 21, makes its way through the said annular space and the aperture 37 into the return pipe 31 to flow to the storage container. Consequently, the apertures 35 and 32 in the subsidiary cylinder 21 for the return pipe 29 and the branch pipe 28 respectively, are again closed by the upper piston 23 of the downwardly moving double piston 22, 23, as also, by the lower piston 22, the aperture 34 of the connecting pipe 27, whereupon liquid under pressure is again forced by the pump 12 into the pressure cylinder 7 and into the auxiliary cylinder 15, so that in the former (7) the driving piston 8, together with the compressor piston 2, and in the latter (15) the piston 16 are again moved upwards. The cycle described is repeated as required for the purpose of maintaining a predetermined temperature.

During the working cycle described, the pressure of the refrigerating medium vapour naturally drops and the temperature falls so that finally,

an inserted regulator effects a current interruption to the motor, and working ceases. The working cycle is again initiated when the temperature in a refrigerating cabinet fitted with the compression refrigerating installation described rises, for example by a prolonged opening thereof, to say 4° C., whereupon the temperature regulator referred to again throws in the electric motor so that the cycle of operations again commences.

The particularly simple design of the refrigerating installation permits of operating with a specially low number of strokes and consequently large cylinder capacity, so that with large dimensioning of the expander surface the expander pressure can no longer fall, for example, more than 0.5 atm. during an inlet stroke of the compressor piston.

A throttling device can be mounted in the return pipe 29 leaving the subsidiary cylinder 21, in order to permit the return flow of the liquid under pressure to the storage container, and thus to regulate the falling or inlet movement of the compressor piston 2.

What I claim and desire to secure by Letters Patent is:

1. A piston compressor type of refrigerating plant comprising a compressor having a cylinder and a piston, the filling stroke of which is produced by the pressure of the vapor of expanded refrigerant, a motor having an operative piston drivingly connected with the compressor piston to produce the discharging stroke of the compressor piston, while the said driving piston partakes of the motion of the compressor piston in its filling stroke, thereby being displaced in the driving motor, said motor having a pressure cylinder in which the driving piston is located, a supply reservoir for operating liquid, a pressure pump for supplying driving pressure liquid to the driving motor, a supply conduit connecting said pump with said motor cylinder, a subsidiary cylinder, an auxiliary cylinder, the subsidiary cylinder and the auxiliary cylinder each being provided with a spring-loaded piston, a conduit connecting the driving motor at an intermediate point of its stroke with the subsidiary cylinder on the opposite side of its piston from its loading spring, a conduit connecting the auxiliary cylinder at a point on the opposite side of its cylinder from its loading spring with a point of the subsidiary cylinder which is blocked by its piston when its spring is fully expanded and is opened when the piston moves to compress its spring, so that the auxiliary piston is then supplied with driving liquid, return pipes leading from the cylinder of the operating motor and from the subsidiary cylinder to the supply reservoir, the piston in the auxiliary cylinder therefore being moved against the force of its piston loading spring, during the pressure stroke of the operating piston, and at the end of the stroke forcing pressure fluid from the motor cylinder to the subsidiary cylinder and moving the subsidiary cylinder piston against the force of its piston loading spring to thereby connect the auxiliary cylinder with the subsidiary cylinder and by means of the subsidiary cylinder piston open the proper return pipe so as to change the compressor piston over to filling stroke, the returning operating piston being thereupon at first temporarily cut off from the pressure cylinder and thereupon connected with its return pipe, the piston of the subsidiary cylinder being then moved by its spring and serving to cut the subsidiary cylinder off from the auxiliary cylinder.

and to close the return pipe of the subsidiary cylinder, thus producing the discharging stroke of the operating piston and again supplying pressure liquid to the auxiliary cylinder.

2. Refrigerating apparatus according to claim 1, and in which the piston in the subsidiary cylinder is a double headed piston, one of which heads of said double piston serves for controlling a connecting pipe provided between the subsidiary cylinder and the auxiliary cylinder and a check valve in the supply pipe of the auxiliary cylinder.

3. Refrigerating apparatus according to claim 1, and in which the operating piston is provided with a peripheral groove for effecting connection of the return pipe of the pressure cylinder with the subsidiary cylinder so as to connect subsidiary

cylinder with the liquid reservoir to allow discharge of the subsidiary cylinder to the reservoir.
